(57) **CLAIM**

I claim, the ornamental design of a weight for balancing and steadyng stemware.

DESCRIPTION

This inventor claims priority from a U.S. utility patent application Ser. No. 11/302,556 filed Dec. 13, 2005.

FIG. 1 is a Front Perspective view as used with stemware.

FIG. 2 is a Top view.

FIG. 3 is a Right Side view.

FIG. 4 is a Top view of the claimed weight for balancing and steadyng stemware, shown with an unclaimed environmental surface pattern

FIG. 5 is a Right Side of the claimed weight for balancing and steadyng stemware, shown with an unclaimed environmental surface pattern; and,

FIG. 6 is a Top Side view with extended fasteners.

The broken line showing of a decorative surface pattern in FIGS. 4 and 5 and the broken lines forming the wine glass in FIG. 1 are all for environmental purposes only and form no part of the claim.
